UNITED STATES PATENT OFFICE.

MITCHEL STERN, OF PHILADELPHIA, PENNSYLVANIA.

BACKREST FOR BATHTUBS.

1,390,221.

Specification of Letters Patent. Patented Sept. 6, 1921.

Application filed June 21, 1921. Serial No. 479,281.

To all whom it may concern:

Be it known that I, MITCHEL STERN, a citizen of the United States, residing at Philadelphia, in the county of Philadelphia and State of Pennsylvania, have invented a new and useful Backrest for Bathtubs, of which the following is a specification.

My invention relates to improvements in devices of the above indicated character designed for use as an attachment for bathtubs, for the convenience and comfort of the bather. The primary object of the invention is the provision of a device which is comparatively inexpensive in cost of production, which is facile in manipulation for attachment to or detachment from the bath tub, and is designed to support or suspend a back-rest of absorbent material, in the form of a mat. The mat is readily attached to or detached from its supporting or suspending device, and may be changed and is adapted for individual use. The invention consists in certain novel combinations and arrangements of parts as will be hereinafter fully pointed out and claimed.

In the accompanying drawings I have illustrated one complete example of the physical embodiment of my invention wherein the parts are combined and arranged according to the best mode I have thus far devised for the practical application of the principles of my invention.

Figure 1 is a face view showing the device of my invention in elevation, as usually supported or suspended from the roll rim of a bath tub.

Fig. 2 is a top plan view of the device in Fig. 1.

Fig. 3 is a view showing in section so much of the end portion of a bath tub as is necessary to illustrate the application thereto of the device of my invention, the pad and suspending device being shown in section also.

In the preferred form of the invention as illustrated in the drawings, the device is to be supported or suspended from the roll rim R of the bath tub T as indicated in Fig. 3 of the drawings.

The suspending device is preferably made up of a single piece of steel wire, possessing sufficient resiliency to enable the user to snap the device over the rim or roll R of the tub, and the suspending device comprises a suspension bar 1 curved to conform to the curvature of the inner face of the

end wall of the usual domestic bath tub. At its ends this bar is bent upon itself forming eyes 2 2', and the short return bars 3 3' extending inwardly therefrom reinforce the suspension bar to provide a rigid and close contact with the inner face of the end wall of the tub. At the inner ends of these return bars said bars are curled over at approximately right angles to the suspension bar as at 4 and 4' respectively, and these curls conform generally to the roll rim R of the tub as shown in Fig. 3, and, together with the curved bar 5 which joins these curls, a wide hook is formed. The steel wire composing the suspension device is of sufficient resiliency, especially in the curls 4 and 4' as to permit the wide hook to be snapped or forced over the top of the roll rim of the tub, and as the suspension bar 70 and hook bar 5 conform to the curvature of the wall of the tub, the device is thus retained in adjusted position on the roll rim, with the suspension bar at the inner side of the tub as shown.

The pad or mat 6, while shown here in rectangular form, may be made in any desired shape, but of sufficient length to depend into the water contained in the tub. The pad or back rest is of absorbent, lofty, material in order that the water, by capillary attraction may permeate the entire area of the pad. Thus with warm water in the tub, the water will be absorbed by the material of the pad for the comfort of the bather and as a protection against the usually cold walls of the bath tub.

The pad is of a width corresponding to the length of the suspension bar 1 and is designed to be suspended at its upper edge 95 from said bar, the pad being turned over the bar at 7, with its overlapping edge 8 at the rear of the bar and against the wall of the tub. By means of a suitable number of snap fasteners 9, similar to glove fasteners, the upper edge of the pad after being turned over the suspension bar, is temporarily, but securely attached to the suspension bar, open notches 10, 10, being provided at the upper edge of the pad for the accommodation of the curls 4 and 4' of the suspension device.

The pads are interchangeable, each individual using his or her own pad, and while the suspension device may remain in position 110 on the tub, if desired, the pads may readily be attached for use and detached after use,

thus providing a sanitary pad for each individual user.

As illustrated the attaching device is covered, and the pad provides a shield for the 5 person of the bather, not only against the walls of the tub, but also against the metal bars of the attaching and suspending device, thus enabling the bather to perform his ablutions with comfort and convenience.

Having thus fully described my invention, what I claim as new and desire to secure by Letters Patent is—

The combination in a back rest for a bath

tub, of a suspending device comprising a suspending bar having bent ends and short 15 reinforcing return bars, each said return bar at its inner end merging into an angularly disposed curl to fit over the roll rim of the tub, and a curved hook bar joining said curls, a pad of absorbent material having a notched upper edge and overlapping said suspending bar and reinforcing bars, and snap fastening devices on said overlapping edge and pad for temporarily securing said pad to the suspending bar.

MITCHEL STERN.
